UNITED STATES PATENT OFFICE.

CHARLES T. E. GOULD, OF CHICAGO, ILLINOIS, ASSIGNOR OF ONE-THIRD TO EDWARD MILKER, OF CHICAGO, ILLINOIS.

SEWING-MACHINE.

1,087,165.

Specification of Letters Patent. Patented Feb. 17, 1914.

Application filed August 9, 1912. Serial No. 714,216.

To all whom it may concern:

Be it known that I, CHARLES T. E. GOULD, a citizen of the United States, residing at Chicago, in the county of Cook and State 5 of Illinois, have invented certain new and useful Improvements in Sewing-Machines, of which the following is a specification.

This invention relates to improvements in sewing machines, and has for one of its principal objects the provision of means whereby the sleeves, legs, and circular portions of garments can be conveniently placed on the machine and manipulated so as to be readily stitched thereby as desired; and also, that the 15 machine may be used for ordinary or plain sewing.

A second object of my invention is the provision of an oil proof casing for the lower operating parts and of means to prevent 20 the spilling of oil if the casing is turned over on one side.

A third object of my invention is to improve and simplify the mechanism for operating the feeding device of the machine and 25 to improve the method of changing the feed.

A fourth object is to improve and simplify the means for retaining the shuttle in a rotary hook or holder whereby the shuttle may be more readily inspected, inserted, and 30 removed, while being held securely in place during operation.

A fifth object of the invention is to provide means whereby the mechanism for operating the feeding device and the bobbin-case 35 may be more conveniently inspected and access thereto easily had.

A further object resides in detailed parts and the arrangement and combination of parts hereinafter described.

40 In the accompanying drawings which serve to illustrate the invention Figure 1, is a front elevation of a sewing machine embodying the improvements. Fig. 2, is a side elevation taken from the left of Fig. 1, the upper part being broken away and part being sectioned on line 2—2, of Fig. 1. Fig. 3, is a plan view of a portion of Fig. 1, parts being removed and parts being broken away. Fig. 4, is a plan view of Fig. 1, with the central cover plate removed. Fig. 5, is a sectional view on the line 5—5, of Fig. 1, parts being broken and the interior mechanism being removed. Fig. 6, is a detail view of the removable piece used to inclose the shuttle 55 mechanism. Figs. 7, 8, and 9, are detail

views showing different methods of retaining the cap piece in place. Fig. 10, is a vertical central section through the left hand portion of Fig. 4. Fig. 11, is a detail plan view of the feeding device and adjoining parts, the central cover omitted in Fig. 4, being shown in place. Fig. 12, is an elevational view partly in section of the parts shown in Fig. 10, and Fig. 13, is a view taken from the same position as Fig. 12, but with the cap piece removed and the gate swung outward as when removing or inserting a bobbin and the case therefor.

Referring particularly to the drawings, 1, is a base plate made integral with the well 2, and the trough or case 3. Mounted on the plate 1, is a casting 4, which supports the driving wheel and the needle operating mechanism. However, my invention does not relate in any way to parts supported by 75 or carried with the casting 4, except as to the feed regulating device described below which lies partly within this casting. It is obvious however, that I intend to drive the wheel 5, by a belt in the usual manner. As 80 shown in Fig. 4, I employ a connecting rod 6, within the casting 4. This rod 6, transmits the motion of the shaft (not shown) of the wheel 5, to a crank 7, attached to the inner or right hand end of a shaft 8, which 85 runs through the length of the trough 3. At the outer or left hand end of the trough 3, is a rotary hook 9, carried and driven by the shaft 8. A bobbin-case 10, is shown in place within the hook in Figs. 10, and 12, but is 90 omitted in Fig. 13. The particular bobbin-case and bobbin mechanism shown are not 95 my invention. At the left of the hook, however, is my improved gate structure 11, for holding the bobbin-case in the hook. This 100 gate may be used in conjunction with any form of rotary machine having a bobbin-case. As shown particularly in Fig. 10, the trough 3, has a vertical integral wall 12, near its left hand or outer end. The wall 12, has 105 a cut-out portion 12^a, into the upper face of which is threaded a screw 13. This screw supports a block 13^a, integral with the bracket arm 14, to the outer end of which the gate 11, is pivoted.

The gate structure comprises an annular ring 15, pivoted to the bracket arm by means of a pin 16, which passes through the arms and two lugs 15^a, integral with the ring 15, which embrace the outer end 110

of the arm 14. The ring 15, as clearly shown in Fig. 10, has its inner edge rounded and when in vertical position bears against the convex outer surface of the bobbin-ease 5 10, holding it securely in place. Pivotally attached to the ring 15, is a latch lever 17, best shown in Fig. 2, and shown in side views in Figs. 10, 12, and 13. The pivot for the latch 17, is furnished by the screw 10, which secures the latch to the ring 15. 10 The block has a hole larger than the screw 13, which allows adjustment of the block 13^a, and consequently of the gate structure. The position of the block is controlled by 15 the screw 10^a, which is adjusted in a hole in the side of the socket 12^a. Carried by 20 the upper face of the wall 12, is a plate 19, the edge of which appears in Fig. 2. Plate 19, is attached to the wall 12, by screws 21, appearing in Fig. 11. Attached 25 to the bottom face of the plate 19, is catch bar 20, secured to the underface of the plate 19, by means of screws 21^a, shown in dotted lines in Fig. 11. This bar has a recess 22, 30 in its outer face as shown in Figs. 2, 10, and 11. One edge of recess 22, is slotted or notched as shown at 23, in Fig. 13. When the gate structure is to be held in the vertical position as shown in Figs. 10, and 12, 35 the lever 17, is pushed to the right as viewed in Fig. 2, the gate swung up into the vertical position and the lever allowed to engage the notch 23. The lever is forced into engaging position by means of the spring 24, 40 which has one end attached to the lever 17, and the other end clasped about a wire loop 25, which is attached in turn to the ring 15. As clearly shown in Fig. 2, the lever 17, extends through the loop. As shown in 45 Fig. 2, the lever 17, has an arm 17^a, also shown in Fig. 11, in dotted lines. The arm 17^a, is bent at right angles at its outer end as shown at 17^b, to serve as a finger piece. Surrounding the bobbin-case mechanism 50 and fitted on to the outside of wall 12, is a cover or cap piece 26, of U-shaped cross section. A detailed perspective view of member 26, is shown in Fig. 6, from which it appears that this member is open at one 55 end and closed by a wall 26^a, at the other end. The top also is open. Member 26, is provided with inwardly projecting webs or flanges 27, at the corners at its top. The flanges 27, are designed to engage the upper faces of projections 28, carried at the ends 60 of the bar 20, for the purpose of holding the cap 26, in position. As shown in Fig. 7, I may provide the member 26, with a projecting arm 29, which is adapted to slide in the rear face of the trough 3. According 65 to the arrangement shown in Fig. 7, the arm 29, is pivoted at 30, to a small bar 31, which slides in the same slot as the arm 29. The bar 31, is formed with a toe 32, at the end opposite the pivot point, and the

pin 33, is provided, to project into the slot sufficiently far to engage the toe 32, whenever the cap 26, is pulled a sufficient distance from its normal position. The extreme position of cap 26, and toe 32, is shown in Fig. 7, in dotted lines. Figs. 8, and 9, show alternative constructions which may be substituted for that of Fig. 7. In Fig. 8, the bar 29^a, is not hinged but is provided with a toe (not shown) similar to toe 32. A pin 75 (not shown) is also provided in this form for the same purpose as the pin 33. In Fig. 9, however, the cap 26, is merely hinged to the trough 3, by hinge 31^a, at its bottom point. Of these constructions Fig. 6, is the 80 preferred form.

The device for feeding the cloth is designated as 34, and consists of three rows of serrated teeth which project through apertures 35, in the plate 19. As shown in Fig. 85 10, the sets of teeth 34, project from the small plate 36, which is provided with an integral arm 37. The arm 37, fits into a notch or shelf on the irregular casting 38. The casting 38, and consequently the teeth 34, are given a horizontal reciprocating motion and at the same time a vertical play by mechanism about to be described. The horizontal movement of the feeding device is caused by a lever arm 39, which has two 90 projecting jaws 39^a, at its left hand or outer end. These jaws 39^a, embrace a block 39^b, which is attached to lugs 38^a, projecting from the member 38, by the pivot pin 40. The arm 39, is pivoted at 41, to a supporting plate 42, integral with and carried by the trough 3, of the machine. Intermediate 100 its ends the arm 39, carries a pivot 43, to which is connected a second lever arm 44, shown in side view in Fig. 10, the shaft 8, 105 has a bearing at 45, in the wall 12. At the inner side of this bearing the shaft 8, carries a cam 46, while the arm 44, is provided at its outer end with a roller 47, which bears upon the outer surface of the cam 46. As 110 the shaft 8, revolves the arm 44, is vibrated. Now the arm 44, is provided with a lug 48, which is bent upwardly at its outer end so as to engage the face of a wedge shaped member 49, carried at the end of a rod 50. 115 Now the lever arm 39, is provided with a lug 51, extending from its lower face and shown in section in Fig. 3. A spring 52, abuts against the inner face of the trough 3, and serves to push the arm 39, and consequently the lug 51, in the direction of the upturned end of the lug 48. Now the rod 50, is pivoted at 53, consequently when the vibration of the small lever 44, moves the wedge 49, into contact with the lug 51, the 120 lever arm 39, is moved in a direction to compress the spring 52, and when the position of the cam 46, permits, the spring 52, pushes the lever 39, and consequently the parts 49, and 44, back to their original positions, 125 130

causing a vibration of arm 39, and a reciprocation of the feeding device, pivoted thereto. The reciprocating motion of the feeding device is guided by the flanges 54, 5 on the member 38, which engage the outer face of the wall 12. The wall 12, has an aperture 55, through which the bar 39, extends and which accommodates the projecting lugs of the member 38, to which the arm 10 39, is pivoted.

The vertical movement of the feeding device 34, is caused by a cam 56, carried on the shaft 8, on the outside of the wall 12, there being a bearing block 57, fastened to 15 the under face of the member 38, and engaging the cam 56. A second bearing block 59, lies between the inner face of cam 56, and the lower flange 54, on the member 38, to guide the reciprocating movement of the 20 feeding device. In order to regulate the amount of the feed the position of the pivot point 53, is made adjustable, being carried on an arm 60, which may be fastened in any desired position by the nut 61, which is ad- 25 justable in the slot 62. Adjustment of the nut 61, longitudinally of the slot moves the pivot point 53, and consequently moves the wedge 49, back and forth between the lug 51, and the end of the lug 48, the length of the 30 throw of the arm 39, being determined by the width of the wedge at the point between the two lugs 48, and 51. As appears in Fig. 10, the lever 39, is inclined downwardly from its point of support and the spring 52, 35 also inclines downwardly to its point of contact with arm 39. It is an important feature of my invention that the base plate 1, is integral with the body of the well 2, and also with the trough 3. This affords a rigid 40 construction giving a firm base for the casting 4, which rests directly on the bed plate as shown in Fig. 4. By having the trough and well integral I avoid the possibility of the escape of oil from joints in the base of 45 the machine, the integral wall 12, at the outer end of the trough 3, assisting in this purpose by preventing the escape of oil from the trough at the outer end. The trough 3, is also provided with recesses or 50 grooves 63, in its upright walls which are designed to catch oil in case the machine is turned over on its side. All oil coming from the trough 3, and the casting 4, collects in the well 2, since the trough and the casting 55 open into the well. The bottom of the well is closed by a removable cap 64, provided with a flange 65, threaded to the exterior of the well. The height of the flange 65, is sufficient to prevent the overflow of oil when the 60 cap is removed for cleaning. The cap piece 26, is also designed with a view to prevent the leakage of oil which may fall into the cap. Around the open end of the cap is a ridge 66, which prevents the oil from creeping out 65 horizontally when the cap is in place, while

the interior of the cap 26, is provided with two grooves 67—67. The trough 3, being integral along the bottom and sides is open at its top to allow access to the interior mechanism for inspection and repair. This feature of having the bobbin case driving mechanism accessible from the top is a marked improvement over prior constructions in which it was necessary to tilt the machine in order to inspect these parts. In 70 order to cover the top of the trough when the machine is in use I provide a plate 68, which is inserted at one end under the edge of the casting 4, while the other end is fastened to the top of the wall 12, by means 75 of the screw 69. At the end of the plate 68, opposite the wall 12, the plate is notched so that it may engage the pin 70, shown in dotted lines in Fig. 4, also appearing in Fig. 5. The casting 4, and the pin 70, hold the 80 inner end of the plate 68, securely in position and yet allow it to be readily moved when the screw 69, is removed.

A marked advantage of my machine over prior constructions, is its adaptability to 90 darning hose and sewing other circular articles. With this object in view I have made the trough 3, small and with regular outline so that a stocking may be readily pulled over it. The special design of my 95 bobbin case and feed driving devices enable me to place them in a small space, thus reducing the necessary size of the trough. Also the bed plate 1, is provided with two 100 long slots or grooves 71, and 72, one on each side of the trough 3, and running parallel therewith, permitting a stocking to be readily drawn over the trough. The edges of the slot 71, and 72, are notched in the usual manner so as to retain long slide plates 105 73, and 74, which may be pushed back to the right under the casting 4, when it is desired to do darning or circular work, but which are placed in position shown in the Fig. 4, when the machine is to be used for other 110 purposes. It is of course necessary that the bed plate 1, shall be entirely disconnected from the trough for a considerable distance in order to follow this method of operation, but the stocking cannot be run on the trough 115 farther than the casting 4, and therefore, beyond this point I make the bed plate integral for mechanical reasons, the opening 71—72, being reduced to mere shallow grooves 71a—72a, in which the plates 73—74, 120 may lie during the darning operation. It will be seen, however, that the casting 4, spans these grooves and rests firmly on the base plate 1.

It will be understood that various modifications and rearrangements of the specific machine shown and described herein may be made without departing from the spirit of my invention.

Having thus fully described my invention 130

what I claim as new and desire to secure by Letters-Patent is—

1. In a sewing machine, the combination with a base plate, of a horizontally extended trough of approximately U-shaped cross section connected to the lower portion of said plate and having horizontally extending grooves angular in cross section in the upper portion of its walls for retaining oil when the trough is placed on its side.

2. In a sewing machine, the combination with a base plate, of a horizontally extending trough connected to the lower portion of said plate and terminating at one of its ends in a well for holding oil drippings, and a detachable cap secured on the lower portion of said well.

3. A sewing machine comprising in com-

bination a horizontal plate provided with two parallel slots extended longitudinally therein, a trough shaped casing open at its top and located intermediate said slots, and a slidable member located in each of said slots and in the opening of the trough to open and close the same.

4. In a sewing machine in combination, a plate, a bar provided with projections at its opposite ends attached to the bottom of said plate, and a cap piece provided with web members for sliding between said plate and said projections to hold said cap in place.
